UNITED STATES PATENT OFFICE.

HARRY J. HAIGH, OF STAPLETON, NEW YORK.

TOY.

1,243,287.

Specification of Letters Patent. Patented Oct. 16, 1917.

Application filed November 29, 1916. Serial No. 134,106.

To all whom it may concern:

Be it known that I, HARRY J. HAIGH, a citizen of the United States, residing at Stapleton, Staten Island, borough and county of Richmond, and State of New York, have invented certain new and useful Improvements in Toys, of which the following is a specification.

My invention relates to improvements in figure toys, and more particularly to toy boats, toy aquatic animals, and the like.

One object of the invention is the provision of simple means for propelling toy objects either upon or beneath the surface 15 of a body of water.

Another important object of the invention is the provision of means for readily and rapidly submerging the toy and bringing it to the surface.

20 A further object of the invention is the provision of simple propelling and submerging devices adapted to be simultaneously or independently controlled.

In the drawings, Figure 1 is a vertical 25 longitudinal section of a toy submarine vessel embodying the invention, the vessel being shown submerged;

Fig. 2 a top plan view of the vessel;

Fig. 3 a side elevation, partly in vertical 30 section, showing the vessel floating on the surface of a body of water;

Fig. 4 a detail perspective view of the device for displacing the water in the hull to raise the vessel;

35 Fig. 5 a detail view of the propelling means; and

Fig. 6 a detail sectional view of an air 40 pump adapted for connection to the outer ends of the air hose to supply air to the propelling and raising means.

Referring, by reference numerals, to the various parts of the embodiment of the invention shown in the drawings, 8 designates the hull of a toy submarine vessel provided 45 with a weighted keel 9 and a pair of horizontal stabilizing fins 10. The vessel is formed with a superstructure 11 upon which a periscope 12 is mounted. The upper end of the periscope 12 is preferably provided 50 with an enlarged buoyant portion or float 13 of any suitable form.

The vessel is provided with a water ballast chamber 15 within the hull 8, and said chamber is connected with the exterior of the 55 hull 8 by a series of passages or conduits 1 through which water is normally adapted

to flow into the ballast chamber to submerge the vessel. If desired, however, the ballast chamber 15 may be omitted and water admitted into the interior of the hull 8 through the openings 1. Closed air chambers 6 and 6^a are provided at the bow and stern of the vessel between the end walls of the ballast chamber 15 and the adjacent ends of the hull 8.

65 A propeller shaft 16 is journaled in a bearing sleeve 17 extending through the hull 8 at the stern of the vessel. A screw or other suitable propeller 5 is mounted on the outer end of the shaft 16 to rotate therewith, and 70 a rotary impact fluid motor 4 is mounted on the inner end of the shaft to drive the propeller 5. The motor 4 is housed in the aft air chamber 6. Motion is imparted to the motor by an air blast from the discharge 75 end 3^a of an air pipe or hose 3, one end of which extends into the chamber 6 and is secured in position to deliver a jet of air against the buckets or blades of the motor 4. The hose or flexible air pipe 3 is provided 80 with a compressible bulb air pump 19, adapted to be held in the hand of an operative and alternately compressed and released to deliver jets of air through the air pipe. The hose is made of sufficient length to enable jets of air to be conveniently delivered 85 against the motor when the vessel is floating on the surface or submerged. A vent pipe 3^c is attached to or formed integrally with the air pipe 3. The inner end of the vent 90 pipe terminates within the chamber 6, and its outer end terminates adjacent the outer end of the pipe 3. This vent pipe serves as an exhaust outlet for the air blown into the chamber 6 to drive the motor 4.

95 An inflatable air bag 7 is provided within the ballast chamber 15, and a flexible air pipe or hose 2 is connected at its inner end with the mouth of the air bag 7. The outer end of the hose 2 is provided with a compressible bulb 19 similar to the bulb 19 of the hose 3. By pumping air into the bag 7 through the pipe 2 to inflate the bag, the water in the chamber 15 may be displaced and forced out through the openings or conduits 1, and the vessel thus caused to rise to the surface.

100 Any suitable form of air-forcing means may be connected to the ends of the air pipes 2 and 3, but I prefer to employ the 110 simple form of air pump shown in the drawings, comprising flexible rubber bulbs

adapted to be attached to the outer ends of the pipes 2 and 3 by any suitable form of coupling. The intake end 18 of each bulb pump 19 is provided with a valve casing 20 containing a freely movable ball valve 21 adapted to close the inlet opening 22 when the end 18 of the bulb is turned downwardly, to prevent air from escaping from the outlet opening. The ball is maintained in the casing 20 by any suitable means, such as lugs 23. It will be obvious that if the bulb is held in the hand with the inlet end 18 lowermost, and alternately compressed and released, air will be taken in through the check valve and forced outwardly through the outlet end 24 and its connected air hose.

The valved pump attached to the air hose 2 for inflating the air bag, also serves as a means for maintaining any desired degree of inflation of the bag 7, and consequently maintaining the toy at various depths below the surface. It is obvious that no air can escape from the bag as long as the bulb is held with the end 18 lowermost so that the ball 21 closes the opening 22.

The pump attached to air hose 3 will deliver successive jets of air against the bucket wheel 4.

The air chambers 6 and 6^a, and the buoyant portion 13 carried by the periscope 12, serve to limit the depth of the submergence of the vessel. The parts are preferably constructed so that the vessel will float in submerged condition with the upper end 13 of the periscope projecting slightly above the surface, as shown in Fig. 1.

From the foregoing it will be observed that a figure toy adapted to float upon a body of liquid has been provided having simple means for causing the toy to submerge, or float upon the surface.

An important feature of the invention is the provision of means for limiting the depth of submergence of the toy. Another important feature is the provision of means for maintaining the toy on the surface or at various levels beneath the surface.

A further feature of importance is the provision of means for propelling the toy either upon or beneath the surface. It will be seen also that simple means has been provided for operating the propelling and raising means either simultaneously or independently, and for controlling the boat while on the surface or submerged.

While I have illustrated and described the invention as embodied in a toy submarine vessel, it will be obvious that the invention may be embodied in many other forms 60 of figure toys, such as various aquatic animals, and other objects.

What I claim is:

1. In a figure toy, the combination of a body portion adapted to float on a body of 65 water, means for normally admitting water within said body portion to submerge the same, an inflatable air bag in said body portion, an air hose connected with said bag and extending outwardly through a wall of 70 the body portion, a pump connected to the outer end of said hose for inflating the air bag, and manually operable means for controlling the exhaust of air from said bag through said air hose to the atmosphere. 75

2. In a figure toy, the combination of a body portion adapted to float on a body of water, means for normally admitting water within said body portion, an inflatable air bag in said body portion, an air hose connected with said bag and extending outwardly through a wall of the body portion, a compressible bulb air pump having its discharge end connected with the outer end of said hose, and a gravity check valve in 85 the intake of said pump, said valve being operable by tilting the bulb pump to maintain the bag in an inflated condition and to permit air to exhaust from said bag. 80

3. In a figure toy, the combination of a 90 hollow body portion adapted to float on a body of water, means for normally admitting water within said body portion to submerge the same, an inflatable air bag within the body portion adapted to displace the 95 water therefrom when inflated, a flexible conduit connected at its inner end with the air bag and extending outwardly through the body portion, a manually operable pump for inflating said air bag connected 100 with the outer end of said conduit, a manually operable valve in the intake of said pump for controlling the exhaust of air from said bag to the atmosphere, an upwardly extending staff fixed at its lower end 105 to the upper side of the body portion, and a float held to said staff to limit the maximum depth to which the body portion may be submerged.

This specification signed this 22nd day of 110 November, A. D. 1916.

HARRY J. HAIGH.
